UNITED STATES PATENT OFFICE

129,994

DESIGN FOR AN ELECTRIC RIM STRETCHER FOR SPECTACLE FRAMES

Julian Gorski, Brooklyn, N. Y.

Application May 22, 1941, Serial No. 101,090

Term of patent 3½ years

To all whom it may concern:

Be it known that I, Julian Gorski, a citizen of Austria, and residing at 500 Washington Avenue, Borough of Brooklyn, county of Kings, and State of New York, have invented a new, original, and ornamental Design for an Electric Rim Stretcher for Spectacle Frames, of which the following is a specification, reference being had to the accompanying drawing, forming a part of the same.

In the drawing:

Fig. 1 is a side perspective view of an electric

rim stretcher for spectacle frames, showing my new design, the opposite side having substantially the same appearance as the side shown;

Fig. 2 is a top plan view thereof; and

Fig. 3 is a side elevational view of the top portion without the base.

I claim:

The ornamental design for an electric rim stretcher for spectacle frames, substantially as shown and described.

JULIAN GORSKI.
